FLAT TUBE ELECTRICAL DEVICE

Eugene Lemmers, Cleveland Heights, Ohio, assignor to General Electric Company, a corporation of New York

Application October 21, 1943, Serial No. 507,073

9 Claims. (Cl. 49—89)

1

This invention relates to electrical devices having tubular envelopes, such as incandescent lamps and heating devices and electric discharge lamps and devices of various kinds, all of which generally have envelopes of vitreous material such as glass or silica.

In the case of fluorescent lamps of the usual low-pressure positive column discharge type in which phosphors are excited by the 2537 Å resonance radiation of mercury, as well as in other resonance radiation lamps (such as germicidal mercury lamps and sodium lamps), it is possible to obtain either greatly improved efficiency of operation or much greater current capacity and discharge wattage when the lamp tube is oval or "flat," rather than substantially circular as in present practice. Also, the light distribution from a "flat" tube lamp is more favorable for some purposes than that from a round tube. But notwithstanding these and other advantages of flat tubes over round tubes, flat tubes as heretofore made have presented a very serious drawback which has prevented their use to any great extent: namely weakness against collapse or implosion by external atmospheric pressure when they are evacuated, even if they contain an atmosphere at greatly reduced pressure, as is usual in ordinary fluorescent lamps and in some other resonance radiation lamps, as well as in tubular incandescent lamps. Because of this, the only flat tube lamp heretofore on the market has been a small, low-wattage fluorescent lamp known commercially as the "T2½ x 6," having a flattened or oval tube about ¾ inch wide by ¼ inch thick, internally, and only 6 to 9 inches long.

I have found a way of overcoming this weakness of flat-tube lamps against external pressure, by putting the longitudinal edges or corners of the flat tube in a state of permanent precompression or bending strain, as I term it. For maximum or assured safe resistance of the lamp against collapse or implosion, the strain in the tube edges may be made so great that even after the lamp is evacuated and the pressure therein is brought to its minimum value during service of the device, a degree of such strain in the edges still remains, over and above that taken up in compensating the external atmospheric pressure on the tube; however, an improvement in the resistance to collapse may be produced even by lower degrees of prestrain or stress in the tube edges. The proper prestraining of the tube edges may be brought about at any convenient stage of tube or lamp manufacture; for example,

5 as an incident of drawing continuous flat tubing from molten glass; or, at the opposite extreme, after a length of tubing has been fabricated into a fluorescent lamp, but before exhausting the lamp.

10 Without attempting to define the possibly beneficial range of tube flatness, it may be said that for the ordinary commercial range of fluorescent lamp tube sizes from 1 inch to 2 inches in internal diameter, flattening to a 4:1 ratio of internal width to internal thickness is very decidedly advantageous, while flattening merely to a 2:1 ratio is about the smallest degree of flattening that is of any real advantage. A strictly flat tube with semicylindrical edges or corners is more advantageous than a pronouncedly oval one; but some slight internal transverse concavity of the wide "flat" walls offers no material drawback. On the other hand, appreciable 15 transverse internal convexity of the wide walls is decidedly to be avoided, because even when slight, it results in a tendency of the discharge to occupy only half the cavity of the tube, or to jump back and forth between the regions at opposite sides of the line of minimum internal thickness of the cavity, instead of constantly filling the whole cross-section of the tube, as is necessary if the advantage of a flat tube is to be realized. Slight internal transverse concavity 20 of the wide walls offers a margin of safety in manufacture against accidental internal convexity of these walls in particular instances.

25 The method of putting the edges or corners of a flat tube under stress which I at present prefer is by heat treatment. For this purpose, the tube is heated above the "strain point" temperature of the vitreous material, and the longitudinal edges of the flattened tube are cooled or chilled below the strain point before its wide and substantially 30 or approximately flat longitudinal walls cool below this temperature. The heating of the tube above its strain point as here referred to may be merely incidental to drawing out and forming the glass into a flat tube, or may be a subsequent heating for the purpose of flattening an initially round-formed tube, or may be a special heating for the main purpose of imposing strain or stress at the corners or edges. The prechilling of the tube edges in advance of the cooling of its wide walls 35 may be effected in a variety of ways: as by blowing cooling fluid (e. g., air) on the edges, wholly or partially to the exclusion of the wide walls; or by heating the wide walls to keep them above the strain point while the edges are freely exposed to be cooled below this point by the cir-

cumambient atmosphere or cooling fluid, and then stopping or reducing the heat to allow the wide walls to cool; or even by merely covering or lagging the wide walls to retain their heat, so that the atmosphere can cool the more exposed edges below the strain point before the wide walls cool down to or below this temperature. The "strain point" here referred to is the temperature below which vitreous material cannot be permanently strained—a particular temperature which is a particular property of every kind of glass or other vitreous material, and generally differs for different materials—all as well understood in the glass art.

It is, of course, important that when a flat tube has had its edges put in strain as described, it should never afterward be heated above the strain point of the material in any subsequent step or operation of lamp manufacture; because this would relieve the strain and destroy the effectual resistance of the tube to external pressure. The usual annealing of the tube as an incident of lamp manufacture must be altogether omitted.

Various features and advantages of my invention will appear from the description of species or embodiments and modes of execution of the invention as applied to fluorescent lamps, and from the drawings.

In the drawings, Fig. 1 is a perspective or tilted view of a form of flat tubular lamp in which my invention may be applied and embodied, portions of the envelope wall being broken out to expose parts within and to shorten the figure; and Fig. 2 is a cross-section of the tube taken as indicated by the line and arrows 2-2 in Fig. 1, and on a larger scale.

Fig. 3 is a side view of apparatus for flattening and straining a lamp tube in accordance with my invention, a portion of the tube being broken out to shorten the figure; and Fig. 4 shows a cross-section through the apparatus and the lamp tube, taken as indicated by the line and arrows 4-4 in Fig. 3.

Fig. 5 is a perspective or tilted view of another form of flat tubular lamp in which my invention may be embodied; and Fig. 6 shows a longitudinal section through one end of the lamp tube shown in Fig. 5, on a larger scale.

Fig. 1 shows a fluorescent lamp L of ordinary low pressure positive column discharge type in which my invention may be embodied. As here illustrated, the circularly round tube ends 10, 10 are annularly reduced or shouldered and are secured in bases 12, 12 each provided with bipost contact terminals 13, 13. As shown at one end of the lamp L, the cathode mount M comprises a cathode 14 of coiled-coil tungsten wire filament type, which may be activated with a coating of alkaline-earth-metal oxide(s), such as the usual mixture comprising barium and strontium oxides. The current in lead wires 15, 15 connecting the ends of the cathode coils 14 to the corresponding biposts 13, 13 are sealed through the stem flares 16 that form the end walls of the tubular lamp envelope, one of which is shown provided with an exhaust tube sealed or tipped off at 18. The leads 15, 15 are shown as provided with anode extensions 19, 19. The lamp tube L may contain a low pressure starting atmosphere of one or more of the inert rare group O gases, such as argon at a pressure of some 2 to 5 mm. of mercury. A supply of ionizable and vaporizable metal to serve as a working substance and provide the discharge atmosphere in operation is also indicated at 20 as a droplet of mercury exceeding in amount what

will be vaporized during the operation of the device. A coating of luminescent material or phosphor is indicated on the inside of the envelope wall at 21, to be excited by the mercury discharge, and especially by its resonance radiation of 2537 Å. wavelength.

As thus far described, the lamp L is essentially similar to ordinary round tube fluorescent lamps now in common use.

Unlike ordinary fluorescent lamps, the lamp tube L is here shown as flattened substantially throughout its length—between the round ends 10, 10 that carry the bases 12, 12—to an elongated loop-like cross section, Fig. 2, comprising wide, flat walls 22, 22 interconnected by the semicircularly rounded envelope edges 23, 23. The round ends 10, 10 may merge into the flattened portion with a wedge-like taper indicated at 24, 24, Fig. 1. It is the rounded edges 23, 23 that are brought into a condition of surface compression in the material in order to render the tube resistant to the external atmospheric pressure.

Figs. 3 and 4 illustrate a form of treating apparatus F which may be used for straining the edges 23, 23 of a flat lamp tube. As shown in Fig. 3, the apparatus comprises counterpart long, flat metal bars 30, 30 (as of iron) which are oppositely and slopingly offset at 31, 31 near their ends, in correspondence to the wedge-like taper of the tube L at 24, 24 in Fig. 1, so that their end portions 32, 32 are further apart than the intermediate portions of the bars. These bars 30, 30 are made substantially narrower than the width of the tube L. Provision is made for maintaining the bars 30, 30 substantially parallel and guiding their relative sidewise movement, as by means of guide rods or pins 33, 33 fixed in the end portions 32, 32 of a bar and extending through corresponding holes in the portions 32, 32 of the other bar; and thus the bars are kept in facial registry or alignment directly opposite one another. Each bar 30 is faced with heat insulating material or lagging to reduce and slow up the transmission of heat from a tube L between the bars to them, as by wrapping asbestos cloth tape 35 around the bar 30 in overlapping convolutions. Preferably this insulation may extend beyond the bar offsets 31, 31, and may nearly cover the bar end portions 32, 32. With each bar 30 may also be associated suitable electrical heating means 37, here shown as a commercial form of strip heater comprising a suitably insulated resistance unit encased in a flattened tubular sheet metal sheath, with terminal connectors or binding posts 38, 38 at each end of the heater 37. Each heater 37 lies along the back side of its bar 30, substantially throughout its length between the offsets 31, 31, and is suitably held thereagainst, as by wrapping the asbestos sheathing 35 around the heater and the bar together.

In using the apparatus F, provision is made to exert a yielding force on the bars 30, 30 to press them toward one another; which may be done by arranging them one directly above the other as shown in Fig. 3, thus taking full advantage of the weight of the upper bar. The bars 30, 30 having been heated up fully by their heaters 37, 37, and an already flattened lamp tube L having been heated well above the strain-point temperature of its vitreous material in any suitable way—as in a heating furnace or lehr, not shown—the heated tube L is placed between the bars 30, 30 as shown in Fig. 3, with the tube resting on the lower bar and the top bar resting on the tube so that the full force of its weight (including that of its

heater 37) is exerted on the tube. This weight is so chosen that the tube L is strained or even further flattened slightly before the exposed edges 23, 23 have cooled off to the strain-point, below which they can no longer be further permanently bent or flattened by the load. While this is taking place, the cooling of the wide, flattened tube walls 22, 22 is limited and retarded by the asbestos facings 35, 35, and also by heat from continued operation of the heaters 37, 37, if necessary, so that the walls 22, 22 do not cool down to and below the strain-point ahead of the edges 23, 23. Once the edges 23, 23 are below the strain-point, however, the heaters 37, 37 may be cut out of circuit so that the walls 22, 22 may cool off below the strain point; and as soon as convenient after this, the tube L may be removed from the apparatus F.

As shown in Fig. 4, the wide walls 22, 22 are very slightly convex outward and concave inward, instead of being perfectly flat as in Fig. 2; but this concavity is so slight as not to impair the advantages of the flat shape appreciably.

Fig. 5 shows a lamp whose envelope tube L is flat right out of its very ends 10a, 10a, which are closed by substantially flat end wall discs 16a, 16a instead of by stem-flares 16, 16 as in Fig. 1. In other respects, the cathode mounts Ma, Ma are just like the cathode mounts M in Fig. 1, and so need not be further described. As shown in Figs. 5 and 6, the end discs 16a, 16a are of sheet metal such as chrome iron, and the tube ends 10a, 10a abut directly against their margins and are sealed to them by fusion of the glass. The extreme edge of each disc 16a is shown in Fig. 6 as turned or beaded over at 40 toward the tube end 10a around the seal, thus protecting the latter and minimizing the possibility of the disc being pulled away so as to impair the seal, by something catching behind the edge, besides stiffening and reinforcing the disc. Each disc 16a is further strengthened by a central inward circular embossment 41 between the current inlead wires 15a, 15a. One of these embossments 41 is apertured through its bottom in correspondence with the end of an exhaust tube fused and sealed to the bottom, and also shelters and protects the exhaust seal tip 18a formed by sealing off the exhaust tube after the lamp L has been exhausted and charged with starting gas and working substance.

Instead of being of usual long bipost type, the contact terminals of each end disc 16a shown in Figs. 5 and 6 are in the form of pins comprising flat or slightly rounded heads 13a, 13a attached (as by welding) to the outer ends of the current leads 15a, 15a, which form the pin shanks, and projecting or outstanding from the outer disc face. For this purpose, insulative spacing washers 42, 42 are interposed between the pin heads 13a, 13a and the disc 16a; they may consist of glass sealed by fusion to the outer disc surface and into the disc holes through which the shanks 15a, 15a extend, as well as to the rear surfaces of the heads 13a, 13a, which may be of chrome iron.

The tube and end construction illustrated in Figs. 5 and 6 lend itself especially to the use of tubing produced directly from the glass batch in flat form, with its edges 23, 23 properly strained. The weakening of the edge strain at the tube ends 10a, 10a in sealing them to the end discs 16a, 16a by fusion is amply compensated by the strength against collapse imparted to the tube ends by their strong attachment to the discs.

In Figs. 3-6, various parts and features are marked with the same reference characters as their counterparts in Figs. 1 and 2, as a means of dispensing with repetitive description, a distinctive letter being added where this seems needful. However, I make no claim to the special end-disc and contact terminal features illustrated in Figs. 5 and 6, since they are the invention of Paul O. Cartun, and are claimed in his application Serial No. 506,230, filed October 14, 1943, which issued as Patent No. 2,415,867, February 18, 1947.

What I claim as new and desire to secure by Letters Patent of the United States is:

1. An envelope for evacuated electric devices comprising a flattened tube of vitreous material having only its longitudinal edges in a state of surface compression sufficient in amount to effectively compensate stresses set up by atmospheric pressure and tending to rupture the tube when it is evacuated.

2. An envelope for evacuated electric devices comprising a flattened tube of vitreous material having rounded longitudinal edges and substantially flat wide walls with only its longitudinal edges in a state of surface compression sufficient in amount to effectively compensate stresses set up by atmospheric pressure and tending to rupture the tube when it is evacuated.

3. In the manufacture of a flattened envelope tube of vitreous material having narrow longitudinal edges and wide longitudinal walls, the method of rendering the tube effectively resistant to collapse by external atmospheric pressure when the tube is evacuated, which comprises subjecting the said longitudinal edges and wide longitudinal walls to different thermal treatments which will produce a state of surface compression in only the said longitudinal edges.

4. In the manufacture of a flattened envelope tube of vitreous material having narrow longitudinal edges and wide longitudinal walls, the method of rendering the tube effectively resistant to collapse by external atmospheric pressure when the tube is evacuated, which comprises heating the tube substantially uniformly over its whole surface to a temperature well above the strain point of the vitreous material and cooling the tube more strongly at said longitudinal edges.

5. In the manufacture of a flattened vitreous envelope tube having narrow longitudinal edges and wide longitudinal walls, the method of rendering the tube effectively resistant to collapse by external atmospheric pressure, when the tube is evacuated, which method comprises chilling the longitudinal tube edges from a temperature above the strain point of the material to a temperature below the strain point in advance of the cooling of its wide longitudinal walls below the strain point.

6. In the manufacture of a flattened vitreous envelope tube having narrow longitudinal edges and wide longitudinal walls, the method of rendering the tube effectively resistant to collapse by external atmospheric pressure, when the tube is evacuated, which method comprises heating the tube above the strain point of the material, exposing its longitudinal edges to cooling fluid but delaying the cooling of its flattened longitudinal walls, until said edges are below the strain-point while said flattened walls are above the strain point, and thereafter also cooling said flattened walls below the strain point.

7. In the manufacture of a flattened vitreous envelope tube having narrow longitudinal edges and wide longitudinal walls, the method of ren-

dering the tube effectively resistant to collapse by external atmospheric pressure, when the tube is evacuated, which method comprises heating the tube above the strain point of the material, cooling its longitudinal edges below said strain point while maintaining its flattened longitudinal walls above the strain point, and thereafter allowing said walls to cool off, as well as said edges.

8. An electric lamp comprising an evacuated elongated envelope of vitreous material, at least a portion of said envelope being flattened and having narrow longitudinal edges and wide longitudinal walls, the said longitudinal edges only of the said envelope being in a state of permanent surface compression. 10

9. An electric lamp comprising an evacuated elongated envelope of vitreous material flattened in cross-section throughout its length, a metallic closure member fused to and closing each end of said envelope, the longitudinal edges only of 15 said envelope being in a state of permanent surface compression. 20
